G. F. SCHENFIELD,
LANDING NET FRAME,
APPLICATION FILED MAY 5, 1915.

1,172,056.

Patented Feb. 15, 1916.

UNITED STATES PATENT OFFICE.

GEORGE F. SCHENFIELD, OF CLARKSTON, MONTANA.

LANDING-NET FRAME.

1,172,056.

Specification of Letters Patent.

Patented Feb. 15, 1916.

Application filed May 5, 1915. Serial No. 26,048.

To all whom it may concern:

Be it known that I, GEORGE F. SCHENFIELD, a citizen of the United States, residing at Clarkston, in the county of Gallatin, 5 State of Montana, have invented certain new and useful Improvements in Landing-Net Frames; and I do hereby declare the following to be a full, clear, and exact description of the invention, such as will enable others 10 skilled in the art to which it appertains to make and use the same.

This invention relates to a landing net frame.

It is designed for the use of fishermen so 15 that the same together with suitable nets thereon may be conveniently folded and placed in the pocket of a person when not in use, yet which may be extended to a full size net when it is desirable to use the same. 20 An object of the invention is to construct a device of this character which may be manually folded to occupy a very small space and which may be locked in such position.

25 A further object of the invention is to so construct the device that upon the releasing of the locking means the frame will be automatically extended into its full size.

With these and other objects in view, such 30 as will appear as the description progresses, my invention comprises the combination and arrangement of parts as set forth in and falling within the scope of the claims.

Referring to the drawing:—Figure 1 is a 35 plan view of my device showing the same in its extended position. Fig. 2 is a sectional view showing the same in its folded position. Fig. 3 is a side elevation thereof. Fig. 4 is a section on line 4—4 of Fig. 1. Fig. 5 40 is a section on line 6—6 of Fig. 1. Fig. 6 is a perspective view of a portion of the device.

Referring to the drawing wherein the parts are indicated by like characters throughout the several views:—My device 45 comprises a head 1 having a longitudinally extending bore therethrough in which is slidably mounted a handle 2 of elongated cylindrical formation. The bore in the head 1 and the handle 2 may, however, be of any 50 desirable formation. Formed on this head 1 is a pair of diametrically oppositely arranged ears 3 and 4 which extend outwardly from the said head and longitudinally thereof.

55 Secured to the ear 3 is a resilient metallic

arm 5 which is of bowed formation and the thickness of which gradually diminishes toward the free end thereof as will be apparent from the drawings. Secured to the opposite ear 4 is a similar arm 6 having a 60 loop 7 on the end thereof. The ends of these arms 5 and 6 overlap and the loop 7 embraces the arm 5 so that the said arms may have motion with relation to each other.

In order that the arms 5 and 6 may be 65 moved upon each other and that the handle 2 may be moved inwardly in the bore in the head 1, I have provided the following mechanism.

In the ears 3 and 4 are formed chambers 70 8 in which are rotatably mounted pulleys 9, the upper ends of the chambers 8 communicate with openings 9' in the face of the head 1. Secured to one end of the handle 2 is a plate 10 having outwardly extending 75 ears 11 thereon through which are formed holes 12. These ears 11 fit into the openings 9' in the head 1 in such manner that the holes 12 therein communicate with the chambers 8 and are directly above the 80 grooves of the pulleys 9 within the said chambers. Secured in these holes 12 are flexible members 13 which pass about the pulleys 9 and thence through grooves 14 in the outer faces of the ears 3 and 4 and are 85 secured to the free end of the arms 5 and 6. It may be thus seen that as the handle 2 is pushed inwardly in the head 1 that the flexible members 13 are pulled about the pulleys 9 and because of the fact that arms 90 5 and 6 are of resilient metal the free ends of the said arms are pulled toward the head 1 in arcuate paths.

While the parts are in the position just described the device is in its folded position 95 and may be readily inserted in a pocket and very conveniently carried.

It is of course desirable to maintain the parts in their folded position against the tendency of the resilient arms 5 and 6 to unfold the said parts and for this purpose, I 100 have provided a metallic lined notch 15 in the handle 2 and in the head 1 a spring pressed catch 16 so that when the handle 2 is moved inwardly the spring pressed catch 105 16 will automatically fit in the notch 15 and lock the parts in their folded positions.

In operation it is merely necessary to push the handle 2 inwardly in the head 1 until the catch 16 drops automatically into the notch 110

15 at which time the arms 5 and 6 have been drawn to this position by the flexible members 13 and inasmuch as the catch 16 is in the aforementioned notch 15 the parts will be maintained in their folded position. To unfold the device it is merely necessary to press the operating lever of the latch 16 at which time the resiliency of the arms 5 and 6 causes the free ends of the same to fly 10 outwardly and to automatically push the handle 2 outwardly from the head 1 and thus completely unfold the device.

It may be thus seen that I have provided a frame for a dip net which may be very conveniently folded and which will be automatic in its opening operation so that it is merely necessary to press a button at which time the frame will be completely open and ready for use.

20 I have so constructed the device that the handle thereof is operatively connected to the net supporting arms in such manner that as the handle is manually pushed within the head in which it is mounted between the net 25 supporting arms the arms will be folded upon themselves and at the same time will be brought under tension so that upon the release of the locking means for the handle the tension will automatically return the 30 handle and the arms to their initial positions.

While I have illustrated and described a particular embodiment of my invention it has merely been done for the sake of convenience and I do not wish to be limited to that particular embodiment for it is obvious that numerous changes may be made within the scope of the invention as defined by the 35 claims.

40 What is claimed is:—

1. In a device of the class described, a cylindrical head, a handle slidably engaged with said head, a pair of outwardly extending bowed arms secured to said head, flexible means connecting the said handle and the 45 said arms, and means pivotally connected to

the head to maintain the handle in a predetermined position.

2. In a device of the class described, a cylindrical head having a longitudinally extending bore therethrough, a handle slidably mounted in said bore, outwardly extending ears formed on said head, bowed resilient arms secured to said ears and arranged in such manner that the ends of the 50 same overlap and flexible members connecting one end of the said handle to the ends of the said arms.

3. In a device of the class described, a head having a longitudinally extending bore 60 therethrough, ears formed on said head and having chambers formed therein, a handle slidably mounted in said bore, pulleys rotatably mounted in said chambers, outwardly extending resilient arms connected to said ears, the free ends of the said arms overlapping and being slidably connected, flexible means connected to the said ends of arms and passing over the said pulleys and operatively connected to the aforementioned 65 handle.

4. In a device of the class described, a cylindrical head having a longitudinally extending bore therethrough, ears formed on the said head and having chambers therein, 75 pulleys rotatably mounted in said chambers, outwardly extending resilient bowed arms connected to the said ears and having the free ends thereof overlapping, a loop on one of said arms slidably engaged with the other arm, flexible means secured to one end of the said handle and passing over the pulleys and operatively connected to the ends of the aforementioned arms, and automatic means 80 for maintaining the said handle and arms 85 in predetermined positions.

In testimony whereof, I affix my signature, in the presence of two witnesses.

GEORGE F. SCHENFIELD.
